UNITED STATES PATENT OFFICE.

WALLACE I. STIMPSON, OF HOPEDALE, MASSACHUSETTS, ASSIGNOR TO DRAPER CORPORATION, OF HOPEDALE, MASSACHUSETTS, A CORPORATION OF MAINE.

SPRING FOR THREAD-CUTTING LOOM TEMPLES.

Application filed March 7, 1928. Serial No. 259,657.

This invention relates to a spring for operating the movable cutter member of a thread cutting loom temple.

Such a temple comprises a body or head 5 presenting a forward and rearward extending guideway in which is mounted the movable cutter member which cooperates with a fixed cutter member to sever the filling ends extending from the selvage. This movable cutter member rocks and slides in the guideway in the performance of its function. The cutting movement is usually given by the lay engaging a heel depending from the movable cutter member, while the return movement to 10 open position is given by a spring connected at one end to the body or head of the temple and at the other end to the cutter member.

Since the movable cutter member is usually actuated at each beat-up of the lay, this 20 spring functions many times every minute. If the spring breaks or works out of position or falls off as a result of wear or as a result of the shock or jar incident to the operation of the loom, the movable cutter 25 member not only fails to function, but may be thrown out of the guideway and thus do considerable damage either to the loom mechanism, to the cloth being woven, or to both.

It is the object of the present invention to provide a spring for this purpose which shall have an easy and uniform action in operating the cutter member, which shall be automatically adjustable to ordinary variations in construction of similar temples, in which there shall be no wear due to adjacent coils rubbing against each other, in which there shall be no tendency for the spring to work or be thrown out of position, and in 40 which there shall be a minimum of wear and strain on the studs to which the spring is connected.

It is the object of the invention further to provide such a spring in which substantially 45 all the spring action takes place in a flat open spiral located parallel with the plane of movement of the cutter member.

It is the further object of the invention materially to decrease or practically to eliminate the breakage of the temple thread cutter spring as a result of the increase in the length 50 of the wire over that employed in the usual types and as a result of the construction by which the coils partaking of the spring action 55 do not contact with or rub against each other.

The object of the invention is further to provide such a spring which may be readily and economically manufactured for use not only with new temples, but for substitution for the springs of existing temples which have become worn or unsatisfactory.

These and other objects and features of the invention will appear more fully from the accompanying description and drawings and will be particularly pointed out in the claims.

While the spring of this invention is adapted for use in connection with a wide variety of thread cutting temples, a preferred embodiment is here shown in connection with a thread cutting temple of the type disclosed 70 in the patent to E. S. Stimpson, No. 1,366,034, January 18, 1921.

In the drawings:

Fig. 1 is a side elevation of the main portion of such a temple with a preferred form 75 of spring embodying the invention.

Fig. 2 is a top plan view of the construction shown in Fig. 1.

The thread cutting temple illustrated as of the type shown in the aforesaid Stimpson patent comprises the usual stand 1 which is mounted on the breast beam of the loom, the shank 2 longitudinally movable in the stand and the body or head 3 having the depending heel 4. As the invention relates entirely to the thread cutting mechanism, no further description of the temple is necessary. The temple head is provided with a vertical slot or guideway 5 which extends through the head or body portion forward and rearward 90 thercof. At the rearward end of this slot or guideway is mounted a fixed cutter blade 6 usually having a rear vertical cutting edge. A movable cutter member cooperates with this cutter blade to sever the filling ends 95 extending from the selvage. This movable cutter member presents a flat body extending through and mounted to slide and rock in the guideway 5. Its rearward end is usually in the form of a hook 7 presenting a cutting edge 8 cooperating with the blade 6, while its forward end is provided with a lateral flange 9 limiting the rearward movement of the member and guiding the rocking and sliding movement of the member in conjunction with the portion 10 of the body or head of the temple. This movable cutter member also has a depending heel 11 in position to be struck by the lay upon the beat-up.

When the lay beats up, it strikes this heel 110

11, giving the movable cutter member a rocking movement thus throwing the hook end 7 downward and then sliding the cutter member forward. The return movement of 5 the movable cutter member into forward open position is given by a spring and it is with this spring that the invention is concerned.

The cutter member operating spring is quite uniformly connected to two studs, 10 namely, a cylindrical stud 12 extending laterally from a point on the body or head or adjacent portion of the shank of the temple, all of which is herein referred to as the temple head, and a cylindrical stud 13 extending 15 laterally from the heel 11 of the movable cutter member. These studs are usually cast integral with the temple head and cutter member, respectively.

The spring of this invention is formed of 20 wire which may be of any suitable cross section, but is preferably of circular cross section and of a suitable spring metal.

The spring comprises, first, a cylindrical section 14 adapted to fit snugly on the stud 12 and thus to hold the spring accurately in position and prevent it from twisting laterally. This cylindrical section is preferably formed by winding the wire into a helical coil and as 25 this coil has practically no spring action in the operation of the spring, the coils of the helix may be wound close together, as shown.

The spring comprises, secondly, an arm 15 at the inner end of the cylindrical section 14 to engage the temple and prevent rotary 30 movement of the cylindrical section on the stud 12. This arm 15 is preferably formed by extending the wire of the helical coil tangentially rearward into engagement with a shoulder 16 on the temple head, preferably 35 grooved to receive the arm.

The spring comprises, thirdly, a flat open spiral 17 lying in a plane normal to the stud 12 and having its axis coincident with the axis of the helical coil or cylindrical section 40 14. With the entire spring formed from a single piece of wire, it will be seen that the outer coil of the helix 14 merges into the inner coil of the spiral. It will also be seen that the flat spiral lies in a plane parallel with the 45 plane of movement of the movable cutter member. This spiral is "open", by which is meant that the coils are separated so that in the operation the spring coils of the spiral do not contact with or rub against each other. 50 Thus the spring action extends throughout the spiral and is a free and easy action and as this spring action takes place in a single plane, there is no tendency to move the entire spring laterally or off the studs or out of position.

The spring comprises, fourthly, a swinging arm 18 extending from the peripheral coil of the spiral 17 and in the plane thereof and adapted at its free or lower end to engage 55 the movable cutter member and particularly the stud 13 thereof. This arm 18 prefer-

ably is tangential with and forms a terminal extension of the peripheral coil of the spiral 17 and swings in the same plane as the spiral so that there is further no tendency, as a result of the swinging movement of this arm, to 70 move the entire spring out of position. This arm 18 preferably has very little spring action in itself because the main spring action takes place in the winding and unwinding of the coils of the spiral. This arm at its lower end 75 is preferably connected to the stud 13 of the movable cutter member and for that purpose terminates in a coil 19 which is made of substantially larger diameter than the diameter of the stud 13. This feature, together with 80 the general construction of the spring, enables the spring to adjust itself automatically to ordinary variations in distance between the studs 12 and 13. Furthermore, the coil 19 and the spiral 17 both lie forward of the arm 18 so that the arm 18 normally stands in substantially vertical position and as the forward and rearward movement of the movable cutter member is comparatively slight, there is 85 little tendency to binding or wear of the parts 90 during the operation of the cutting mechanism.

There is thus presented a spring that may be readily and economically manufactured, that may be readily formed to fit any of the 95 usual type of temples, either by varying the length of the arm 18 or the length of the helical coil 14, or both. The spring is subject to practically no tendency to wear or breakage. In the functioning of the spring, none of the 100 coils rub against each other and there is no tendency to shift or move the spring out of position or to cause it to work off laterally from the studs. Substantially all the spring action takes place in the flat spiral in 105 a plane parallel with the plane of movement of the cutter member and in a free and easy manner.

Having thus described the invention, what is claimed as new, and desired to be secured 110 by Letters Patent, is:

1. A one-piece wire spring for operating the cutter member of a thread cutting loom temple comprising a coaxial helical cylindrical coil and flat open spiral, the helical coil being adapted to fit snugly the usual stud on the temple head and terminating at its inner end in a tangential shoulder-engaging arm and merging at its outer end into the center coil of the spiral with the peripheral 115 coil of the spiral terminating in a tangential arm adapted to engage at its free end the usual movable cutter member.

2. A one-piece wire spring for operating the cutter member of a thread cutting loom 120 temple comprising a coaxial helical cylindrical coil and flat open spiral, the helical coil being adapted to fit snugly the usual stud on the temple head and terminating at its inner end in a tangential shoulder-engaging 125 coil of the spiral terminating in a tangential arm adapted to engage at its free end the usual movable cutter member.

arm and merging at its outer end into the center coil of the spiral with the peripheral coil of the spiral terminating in a tangential swinging arm having at its free end a coil of larger diameter than, and thus adapted to fit loosely, the usual stud on the movable cutter member.

3. A spring having the construction defined in claim 2, in which the said swinging arm extends at the rear of both the spiral and the coil at the free end thereof.

4. A spring having the construction defined in claim 1, in which the wire is of circular cross section.

15 5. A one-piece wire spring for operating the cutter member of a thread cutting loom temple comprising a cylindrical section adapted to fit snugly the usual stud on the temple head and to hold the spring against lateral twisting, an arm at the inner end of 20 said cylindrical section to engage the temple and prevent rotary movement in one direction on the said stud, an open flat spiral lying in a plane normal to said stud and coaxial 25 with said cylindrical section and having its

central coil merging thereinto, and a swinging arm extending from the peripheral coil of the spiral in the plane thereof and adapted to engage at its free end the usual movable cutter member.

30 6. A one-piece wire spring for operating the cutter member of a thread cutting loom temple comprising a cylindrical section adapted to fit snugly the usual stud on the temple head and to hold the spring against lateral twisting, an arm at the inner end of 35 said cylindrical section to engage the temple and prevent rotary movement in one direction on the said stud, an open flat spiral lying in a plane normal to said stud and coaxial 40 with said cylindrical section and having its central coil merging thereinto, and a swinging arm extending from the peripheral coil of the spiral in the plane thereof and terminating at its free end in a coil of larger diameter than, and thus adapted to fit loosely, 45 the usual stud on the movable cutter member.

In testimony whereof, I have signed my name to this specification.

WALLACE I. STIMPSON.
